UNITED STATES PATENT OFFICE.

JOHN F. MURPHY, OF WORCESTER, MASSACHUSETTS, ASSIGNOR OF ONE-HALF TO HAMILTON B. WOOD, OF WORCESTER, MASSACHUSETTS.

METHOD OF MAKING WOOD-BASE CUTTING DIES.

1,402,526.

Specification of Letters Patent.

Patented Jan. 3, 1922.

Application filed September 29, 1920. Serial No. 413,642.

To all whom it may concern:

Be it known that I, JOHN F. MURPHY, a citizen of the United States, residing at Worcester, in the county of Worcester and 5 Commonwealth of Massachusetts, have invented a new and useful Improvement in a Method of Making Wood-Base Cutting Dies, of which the following, together with the accompanying drawings, is a specification.

10 The present invention relates to the manufacture of dies, and in particular to an improved type of wood base die, wherein it is possible to obtain a maximum of accuracy in fitting the cutting blades to the wood base 15 or backing, and at the same time permit of said blades being suitably hardened and tempered.

The invention, involving various new departures in the manufacture of wood base dies, is fully set forth in the following description, reference being had to the accompanying drawings, wherein—

Fig. 1 is a plan view showing the preliminary formation of the design for the die in 20 a block of relatively soft wood.

Fig. 2 is a perspective view showing the die blades temporarily in place in said block.

Fig. 3 is a plan view showing the imprint of said die blades on a permanent block of 30 hard wood which is to form the base of the die.

Fig. 4 is a perspective view showing the manner of removing the die blades from the temporary support, and

35 Fig. 5 is a sectional view showing the manner of inserting the tempered die blades in the permanent base of backing.

Like reference characters refer to like parts in the different figures.

40 The manufacture of a wood base die as at present practiced, involves, generally speaking, the sawing of the desired outline or pattern in a suitably prepared block of wood; the die pieces, having been shaped or bent 45 to conform as nearly as possible to the outline as cut by the saw, are inserted and worked into the kerf.

The results of this process are in the main 50 unsatisfactory; it is practically impossible, owing to variations between the blade pieces and the saw kerf, to obtain a firm enough setting of the blades which will enable the die to stand up under continued and prolonged hard usage; moreover, when the pattern or outline involves sharp reentrant

turns or angles, the metal of the blade, as inserted in the saw kerf, must be soft enough to permit of being forced and bent into such angles, and, consequently, is precluded from having the proper hardness and temper in 60 the completed die.

The above and other defects and shortcomings in the manufacture of wood base dies are overcome in the process of manufacture contemplated by my invention, in 65 the following manner:—The outline of the pattern is first laid off on a non-permanent block of wood, preferably of a relatively soft laminated piece, and this outline is sawed, as shown in Fig. 1, so as to provide a continuous 70 kerf or slot 1 between the body 2 of the block and the inner portion 3. The die blade material, in relatively soft untempered form, and in a plurality of pieces, as indicated in Fig. 2, is worked and bent into such shape 75 as to conform to the outline, being inserted and held in the kerf 1 between the portions 2 and 3, in the manner well known in the art. When this has been done, the assembly is in all essential respects the counterpart and 80 equivalent of the wood base dies now in ordinary use, as above described. The mode of manufacture of my improved die, starting from this point, is as follows:—

The assembly of Fig. 2 is used for the purpose of making a true imprint of the die blade on a hard block of wood 4, which is preferably of the usual laminated formation. This impression or outline is the actual 85 outline of the completed die, and it differs 90 in most cases from the original outline 1 of Fig. 1, for the reason that it is never possible to make the metal conform absolutely to said original outline. Hence this second outline on the permanent hard block 4, is one which, 95 when sawed, will conform absolutely to the bent metal, as distinguished from the approximate conformation between saw kerf 1 and the bent metal. In other words, the saw kerf 5 in the permanent block 4 is cut to the exact form and configuration of the formed die blades, whereby an exact and accurate fit is assured; on the other hand, no such fit can be obtained in the assembly 100 shown in Fig. 2, since the metal can never be bent and shaped accurately enough to fill all the interstices and crevices of the saw kerf 1.

The next step in my improved method is 105 the removal of the blade pieces from the non-

permanent block; this is done by cutting and breaking away the outer and inner portions 2 and 3, as indicated in Fig. 4. The shaped and formed blade, freed as a result 5 of this operation, can now be hardened and tempered to any desired degree, since it is no longer necessary to retain the material in ductile form; the slot or kerf 5 into which it is to be inserted, has been given the precise form required. After hardening and 10 tempering, the blade pieces are entered, cutting edge first, into the kerf 5, the latter preferably being a few thousandths of an inch narrower than the blades, so that said 15 blades must be forced into the kerf by the exertion of considerable pressure. To accomplish this result and, at the same time, guard against the collapse of the inner base portion 6, the blade pieces are forced 20 through the kerf in a suitable press, as indicated in Fig. 5, so arranged that the cutting edges, as they project downwardly through the kerf, come into contact with a yielding surface, preferably provided by a 25 block 7, set in opposition to the permanent block 4 and having its grain running lengthwise at right angles and perpendicular to the grain of the block 4.

By this process the blade pieces are driven 30 through, compressed and held in a kerf which corresponds exactly to their outline, the cutting edges imbedding themselves in a surface which is maintained at all times in close contact with the surface of portion 6, 35 thus preventing breakage and collapse of the latter. After the die blades have thus

been set into place, the block 7 is broken or driven off, leaving the completed die accurately fitted and held in its permanent wood base.

I claim,

1. The herein described method of making a wood base die, which consists in forming and fitting the die blades to a temporary kerf or slot of the desired design, and thereafter inserting said blades in a kerf or slot which is cut to conform to the actual outline produced by said blades, as shaped to and held in said first mentioned kerf.

2. The herein described method of making a wood base die, which consists in reproducing the actual outline of the formed die blades as held in a temporary support upon a permanent die base, tempering said blades after removal from said temporary support, and inserting them in a kerf or slot that conforms to the outline reproduced in said permanent base.

3. The herein described method of making a wood base die, which consists in forming and working the die blades as closely as possible to a slot or kerf of the desired design, taking the imprint of said blades, as held temporarily in said slot or kerf, upon a permanent wood base, forming a slot or kerf upon said imprint, supporting said permanent base against the grain end of a block, and forcing said blades through said slot or kerf, to imbed themselves in the end of said block.

Dated this 27th day of September, 1920.

JOHN F. MURPHY.
